UNITED STATES PATENT OFFICE.

HENRY S. BREWINGTON, OF BALTIMORE, MARYLAND.

BOTTLE-STOPPER.

SPECIFICATION forming part of Letters Patent No. 703,527, dated July 1, 1902.

Application filed November 9, 1901. Serial No. 81,749. (No model.)

To all whom it may concern:

Be it known that I, HENRY S. BREWINGTON, a citizen of the United States, residing at Baltimore city, in the State of Maryland, have 5 invented certain new and useful Improvements in Bottle-Stoppers; and I do declare the following to be a full, clear, and exact description of the invention, such as will enable others skilled in the art to which it appertains 10 to make and use the same, reference being had to the accompanying drawings, and to the figures of reference marked thereon, which form a part of this specification.

My invention relates to bottle-stoppers, and 15 more particularly to bottle caps or seals; and its object is to provide improved means for securing a seal in position upon the mouth of a bottle.

The invention consists in the combination, 20 with a bottle-neck formed with an external annular groove near its upper end, of a seal of sheet metal comprising a disk and a depending annular flange formed with slots to provide pendent fingers and securing-lips alternating with said fingers.

The improved seal will be fully described hereinafter in connection with the accompanying drawings, which form part of this specification, and its novel features will be defined 25 in the appended claims.

In the drawings, Figure 1 is a view in perspective of my improved cap as it appears before its application to the bottle. Fig. 2 is a 30 vertical section of a bottle-neck with the cap in position thereon, and Fig. 3 illustrates a modification.

The reference-numeral 1 designates a bottle-neck formed with an external annular shoulder 2 and groove 3 and adapted to have 35 my improved seal applied thereto. The seal comprises a disk 4 of thin sheet metal, having a depending annular flange 5, formed with a series of parallel slots 6 to provide pendent fingers 7. The width of the slots is preferably about equal to the width of the fingers 40 7, and the lower edges 8 of the flange 5 between the fingers constitute securing-lips to engage below the shoulder 2 of the bottle-neck. A packing 9, of cork or other suitable 45 material, is applied to the under surface of the disk 4. The cap is fitted upon the bottle-neck, and the flange 5 is then crimped or compressed below the shoulder 2, as shown in 50

Fig. 2. The fingers 7 extend well below the shoulder 2 and into the groove 3, and the 55 lower edges 8 of the depending flange also engage below the shoulder 2 and constitute securing-lips, alternating with the fingers 7. It will thus be seen that the seal is secured by two independent sets of fastening devices, 60 which supplement and coact with each other to insure a firm attachment of the seal.

An important advantage of the improved construction is that the spaces between the pendent fingers provide seats or notches to 65 be engaged by an extractor, and the removal of the cap is thus greatly facilitated.

A further feature of importance is that the inwardly-bent securing-lips 8 are strengthened and reinforced by the pendent fingers, 70 and the necessity of employing a tie-wire or other supplemental fastening means is entirely avoided.

In the modification shown in Fig. 3 the edges of the flange between the fingers are 75 projected downward to form lips 8^a, which serve the same purpose as the lips 8, being merely prolongations or extensions of the latter. These lips 8^a, as shown, are shorter than the pendent fingers. 80

I claim—

1. The combination with a bottle-neck formed with an external annular shoulder, of a seal comprising a disk of sheet metal, and a depending flange formed with a series of 85 slots to provide a continuous row of pendent fingers, said fingers and the portion of the flange between the fingers being compressed below the shoulder of the bottle-neck.

2. The combination with a bottle-neck formed with an external annular shoulder, of a seal comprising a disk of sheet metal and a depending flange formed with a series of slots to provide a continuous row of pendent fingers, said fingers being compressed below the 95 shoulder of the bottle-neck, the portion of the flange between said fingers being projected downward and also compressed below the shoulder.

In testimony whereof I affix my signature in presence of two witnesses.

HENRY S. BREWINGTON.
